(57) **CLAIM**

The ornamental design for a shower bench, as shown and described.

DESCRIPTION

FIG. 1 is a side top perspective view of a shower bench according to the present invention;

FIG. 2 is a side top perspective view of the shower bench illustrated in FIG. 1 in an alternate configuration with the tray removed;

FIG. 3 is a front view of the shower bench illustrated in FIG. 1.

FIG. 4 is a top view of the shower bench illustrated in FIG. 1.

FIG. 5 is bottom view of the shower bench illustrated in FIG. 1; and,

FIG. 6 is side view of the shower bench illustrated in FIG. 1. The broken lines shown in FIGS. 1-3 and 6 depict environmental features that form no part of the claimed design.
